UNITED STATES PATENT OFFICE.

LE ROY E. MORRIS, OF SALEM, OHIO.

DESIGN FOR A COMBINED CLOCK CASE AND CABINET.

Application filed November 30, 1921. Serial No. 519,000. Term of patent 14 years.

To all whom it may concern:

Be it known that I, LE ROY E. MORRIS, a citizen of the United States of America, residing at Salem, in the county of Columbiana and State of Ohio, have invented a new, original, and ornamental Design for Combined Clock Case and Cabinet, of which the following is a specification, reference being had to the accompanying drawings, forming a part hereof.

The figure is a perspective view showing my new, original and ornamental design for combined clock case and cabinet.

I claim:—

The ornamental design for a combined clock case and cabinet as shown.

LE ROY E. MORRIS.
